UNITED STATES PATENT OFFICE.

ERNST F. STECK, OF CHICAGO, ILLINOIS, ASSIGNOR TO THE FIRE EXTINGUISHER MANUFACTURING COMPANY, OF NEW YORK, N. Y.

WATER-TOWER.

SPECIFICATION forming part of Letters Patent No. 654,814, dated July 31, 1900.

Application filed April 6, 1900. Serial No. 11,814. (No model.)

To all whom it may concern:

Be it known that I, ERNST F. STECK, a citizen of the United States, residing at Chicago, in the county of Cook and State of Illinois, have 5 invented certain new and useful Improvements in Water-Towers, of which the following is a full, clear, and exact specification.

My invention relates to that class of water-tower fire apparatus in which the stand-pipe 10 of the tower is provided with means for bending the nozzle to depress the stream and means for rotating it for deflecting the stream from side to side; and my invention has for one of its objects to provide a simple and efficient 15 joint between the rotary and the non-rotary portions.

Another object of my invention is to provide a tight and simple joint for connecting the flexible portion of the nozzle to the stand-pipe of the tower.

With these ends in view my invention consists in certain features of novelty in the construction, combination, and arrangement of parts by which the said objects and certain 25 other objects hereinafter appearing are attained, all as fully described, with reference to the accompanying drawings, and more particularly pointed out in the claims.

In the said drawings, Figure 1 is a side elevation, partly in vertical section and partly broken away, of a stand-pipe of a water-tower embodying my improvements. Fig. 2 is an enlarged vertical sectional view of the aforesaid joints; and Fig. 3 is a transverse section 35 taken on the line 3-3, Fig. 2.

1 represents a stand-pipe, to the lower end of which the hose 2 from the engine or pump is coupled by any suitable means, and on the upper end of this stand-pipe 1 is revolvably 40 mounted a sleeve 3, to whose lower end is secured a gear-wheel 4, which meshes with a pinion 5, having an operating-rod 6, as usual, and being mounted in a bracket 7, clamped to the stand-pipe 1. The upper end of the 45 pipe 1 is provided with an enlarged shoulder or flange 8, which is preferably formed separately therefrom and secured thereto by means of screw-threads, it being held against screwing off by set-screws 9 or other suitable 50 devices, and the upper end of the sleeve 3 is flared outwardly or enlarged, as shown at 10,

so as to constitute a peripheral recess for the reception of the flange or shoulder 8. The mouth of the enlargement 10 is internally screw-threaded, and in it is screwed a coupling member 11, which fits down tightly against the flange 8, and in order to insure against leakage the flange 8 has an annular feather 12 let into the lower face of the coupling member 11, and as a further safeguard 55 an annular gasket 13 is located between the face of the coupling 11 and the flange 8 and let into both of them, thus insuring against leakage over the top of the pipe 1, and thence down between said pipe and the sleeve 65 3, and at the same time providing a joint capable of permitting of the free movement of the latter. The coupling member 11 is prevented from working out of the mouth of the enlargement 10 by keys 14, screw-threaded 70 partly in the coupling member 11 and partly in the sleeve portion 10.

15 represents the flexible portion of the nozzle, whose lower end is provided with a shoulder 16, which is inserted into the coupling 75 member 11 and rests upon a flange 17, formed on a stiffening or reinforcing ferrule 18, which is inserted in the lower end of the flexible portion 15 of the nozzle, and surrounding the nozzle 10, just above the shoulder 16, is a ring 80 19, composed of metal or other rigid substance, while screwed into the coupling member 11 is the lower end 20 of one of the nozzle-controlling members 21. By this means it will be seen that when the portion 20 is screwed firmly 85 down into the coupling member 11 it will impinge the ring 19 and, forcing it against the shoulder 16, will compress the latter against the flange 17, and this in turn will be forced against an internal peripheral flange 22, 90 formed in the coupling member 11, a gasket 23 being interposed between the flanges 17 and 22, the pressure against the ring 19 swelling the rubber shoulder 16 and causing it to fit snugly in the coupling member 11. 95

By the described means it will be seen that I am enabled to employ a rigid stand-pipe 1 throughout the greater height of the tower and at the same time provide the nozzle with the desired degree of flexibility and also with 100 means whereby it may be deflected from side to side.

Having thus described my invention, what I claim as new therein, and desire to secure by Letters Patent, is—

1. The combination of a stand-pipe having a flange attached to the upper end thereof, a sleeve inserted over the end of said pipe and having a circumferential recess receiving said flange for holding said sleeve against movement in one direction, a coupling member secured in the end of said sleeve over and against said flange for holding said sleeve against movement in the opposite direction and a nozzle mounted on said coupling member, substantially as set forth.
- 15 2. The combination of a stand-pipe, a flange secured to the upper end thereof, a rotary sleeve fitted over said stand-pipe and having its upper end enlarged to receive said flange, a coupling member screwed into said enlarged end of the sleeve against said flange, a gasket interposed between said flange and the part contiguous thereto and a nozzle carried by said coupling member, substantially as set forth.
- 20 3. The combination of a stand-pipe, a flange screwed on the upper end thereof, means for holding said flange against unscrewing movement, a sleeve rotatably mounted on the upper end of said stand-pipe and having an enlarged mouth at its upper end receiving said flange, a coupling member screwed into said mouth and bearing against said flange, an annular gasket concentric with said sleeve let into said flange and the part contiguous thereto and a nozzle carried on said coupling member, substantially as set forth.
- 25
- 30
- 35

4. The combination of a stand-pipe, a rotary sleeve thereon, a coupling member carried by said sleeve and having an internal flange, a flexible nozzle having an external shoulder fitting in said coupling member above said flange and the portion 20 screwed into said coupling member above said shoulder for forcing it toward said flange, substantially as set forth.

45 5. The combination of a stand-pipe, a rotary sleeve thereon, a flexible nozzle, a coupling member carried by said sleeve and having an internal flange, a flanged ferrule inserted in said nozzle above the flange of said coupling member, a shoulder formed on said nozzle above the flange of said ferrule and the portion 20 screwed into said coupling member above the shoulder on said nozzle, substantially as set forth.

50 6. The combination of a stand-pipe, a rotary sleeve thereon, a coupling member carried by said sleeve and having an internal flange, a flexible nozzle having an annular peripheral shoulder inserted in said coupling member, a ferrule inserted in said nozzle and having a flange engaging under said shoulder above said flange in the coupling member, a ring surrounding said nozzle above said shoulder and the portion 20 screwed into said coupling member and bearing against said ring, substantially as set forth.

55 ERNST F. STECK.
